UNITED STATES PATENT OFFICE.

WILLIAM W. LEWIS, OF CINCINNATI, OHIO.

BALANCED STEAM-VALVE.

SPECIFICATION forming part of Letters Patent No. 337,688, dated March 9, 1886.

Application filed October 27, 1884. Serial No. 146,638. (No model.)

To all whom it may concern:

Be it known that I, WILLIAM W. LEWIS, a citizen of the United States, residing at Cincinnati, Ohio, have invented new and useful 5 Improvements in Balanced Steam-Valves, of which the following is a specification.

My invention relates to steam-engines, having more particular reference to improvements in the construction and arrangement of 10 balanced slide-valves, which improvements, though applicable to all slide-valve engines, are more especially useful in locomotives operating on railways and road or "traction" engines.

These consist, first, in the construction and arrangement of a balancing plate and piston, in connection with the valve-chest and its cover, for relieving the steam-pressure upon the valve; secondly, in a valve having a recessed back, in combination with the balancing-plate and a hollow piston-rod, forming at the same time a vacuum-chamber and oil-feeding reservoir; thirdly, in the provision and arrangement of an external spring in connection with and acting upon the balancing-plate; fourthly, in the construction of the piston; fifthly, in the construction of the joint-connection between the balancing-plate and its supporting piston-rod; sixthly, in the provision and arrangement of oil-channels in the steam-chest cover, balancing-plate, and valve adapted to secure perfect lubrication of the valve upon its seat and against the balancing-plate.

Mechanism embodying my invention is illustrated in the accompanying drawings, in which Figure 1 is a longitudinal sectional elevation of the valve-chest and auxiliary cylinder, showing the balancing-plate, valve, balancing-piston, and spring in position, and indicating the construction and relation of the parts; Fig. 2, a plan of the valve-chest with one half of the cover removed and the remaining half of the cover sectioned 40 through the auxiliary cylinder on the plane xx of Fig. 1; Fig. 3, a front elevation of the valve-chest and auxiliary cylinder, one-half being sectioned in a central vertical plan; Fig. 4, a plan view of the valve-chest and auxiliary cylinder, one-half of the cover of the latter being removed and the auxiliary

cylinder sectioned above the piston. Fig. 5 shows a weighing apparatus, as hereinafter explained; Figs. 6 and 7, a longitudinal sectional elevation (side) and a plan of a modified form of valve construction. 55

Referring to the drawings, in which the parts designated are indicated by letters of reference, A is the auxiliary cylinder, cast upon the valve-chest cover J; B, the piston 60 operating therein; a, the piston-rod projecting downward into the valve-chest and carrying at its lower end a plate, P, resting in sliding contact upon the valve D; k, the actuating-rod of the slide-valve, and k' the yoke securing the rod k to the valve D; E E', the inlet-ports for admission of steam to the valve-chest, and F G' the receiving and exhaust ports, respectively, in the valve-seat, communicating with the cylinder. 65

The general arrangement of the auxiliary cylinder upon the valve-chest cover and the piston with rod supporting a plate within the valve-chest in sliding contact with the valve is the same as in other structures of this nature, except in so far as modified by my improvements, as set forth in the following description. Instead, however, of leaving the lower end of the auxiliary cylinder entirely open into the valve-chest, I construct the 70 valve-chest cover as a substantially continuous plate with openings b b, constituting steam-passages connecting the interior of the auxiliary cylinder with that of the valve-chest, and a central opening through a thickened 75 boss, b', for the passage of the piston-rod a. This construction not only secures uniformity in the expansion and contraction of the cover and cylinder parts, but furnishes a guide-bearing for the piston near the balancing- 80 plate, which enables it to more perfectly support and retain the latter in position against the lateral strains of friction. 85

The auxiliary piston-rod is preferably constructed of steel turned to different dimensions at different portions of its length, as shown in Fig. 1, is hollow throughout its length, and extends upward through the auxiliary cylinder, and through an arch-piece, h', formed upon the cover H of the auxiliary cylinder. The hollow cavity through the rod a 90 opens into a depression, d, in the upper side 100

of the valve D, used as an oil-chamber supplied through the hollow piston-rod. The plate P is centrally perforated, and adjustably held upon the piston-rod *a* by a terminal shoulder upon the latter, and a screw-nut, *e*, threaded above the same. The piston B is similarly held upon the rod against a shoulder turned upon the latter by nut *h*.

Since in practice it is desirable to obtain a perfect balance of the plate P by steam-pressure upon the piston B, in order to relieve the valve as much as possible, (as the sudden and irregular movements of the engine in traversing rough roads are likely to lift the plate at times from the valve,) I arrange a coiled spring surrounding the piston-rod *a* above the cylinder A and within the arch-piece *h'*, bearing against an adjustable nut, *e'*, upon the piston-rod. The action of the spring assists the weight 15 of the balancing piston and plate, and being unaffected by the jolting of the engine, as is the weight of the parts, tends to preserve constant contact between the valve and its balancing-plate. The bearing-surface of the nut *e* and 20 its seat are so fitted as to allow a slight variation from a rigid right-angled position of the piston-rod and balance-plate, the joint being a species of "ball-joint," and the foot of piston-rod and its seat are likewise treated. The 25 piston B of the auxiliary cylinder is held against the shoulder on the hollow piston-rod *a* by a nut, *h*, Fig. 1, and over this is slipped a follower, S, perforated, as shown in plan section, Fig. 4. The latter serves, in connection 30 with the bottom plate of the piston-head B, to clamp the packing material in the outer edge of the piston against an adjustable annular rim, *c*. Radial screws *i* bear on the inner circumference of the latter, threaded in an 35 upwardly-projecting annular lug on the piston-head. Vertical screws hold the follower to the annular lug, and by means of the perforations the adjusting-screws *i* are accessible for purposes of enlarging the packing or otherwise. 40 These may be placed at as many and convenient intervals as thought necessary to secure proper and even adjustment. The construction of the auxiliary cylinder gives easy 45 access to its interior, whether the engine be in operation or at a stand. The simple form of the slide-valve allows the exhaust-cavity to be extended in length and the height of the same reduced, whereby a gain is secured in cost 50 from the consequent reduction in the height of the steam-chest.

The countersunk chamber in the back of the valve being filled with oil, thereby preventing access of air or steam, serves practically as a vacuum-chamber, maintaining a close 55 union between the balancing-plate and the valve, enabling me to increase the upward "lift" of the plate, so as to act similarly upon the valve and counteract its weight, or, even by means of suitable weighing apparatus, to determine such weight or downward pressure 60 when under strain. The oil likewise assists, incidentally, in the proper lubrication of the

moving faces, and through the medium of oil-holes in the valve the face and seat of the valve are likewise lubricated. A circular oil-chamber, O, within the steam-chest cover gives additional means of lubrication, and with the oil-holes through the balance-plate allows more perfect lubrication of the valve-seat.

I have shown in Fig. 5 an ordinary scale-beam with weights, adapted at one end for connection with the projecting hollow piston-rod *a*, and at the other for the attachment of suitable weights, the fulcrum being between. By means of this apparatus the actual equilibrium maintained at different parts of the stroke may be measured, the force necessary to raise the valve and balance-plate being made apparent by the amount of weight on the scale-beam, whereby the engine-builder 80 may be the better guided in proportioning the parts of the valve.

Figs. 6 and 7 show a modified form of construction. I pass the hollow piston-rod *a* through a stuffing-box in the steam-chest cover 90 containing a gland, allowing proper packing to be done, as ordinarily, and attach the other end to a steel or other elastic tension-plate, G, supported by the studs T (two or more) upon the cover. These are adjustable in their seats, 95 and by them the proper adjustment of the tension-plate may be effected to secure the most complete balance of the valve. As before, the weighing method may be employed to determine the equilibrium maintained by 100 the balance-plate and valve. In the latter modification the balance is performed by a tension-plate instead of the steam, and it will be evident that, as in the other form, a rigid arch might be constructed on the valve-chest 105 cover and suitable elastic spring or springs introduced instead of a tension-plate, or that more than one tension-plate might be used. I consider these variations as a part of my improvement.

I am aware that balanced valves are not new; that they have before this been constructed with an auxiliary cylinder upon the steam-chest cover containing a balancing-piston and carrying a balancing-plate bearing 115 upon the slide-valve, wherein a spring surrounding the piston-rod above the balancing-piston furnishes the slight excess of downward force required to keep the valve seated. I do not, therefore, broadly claim such construction.

I claim and desire to secure by Letters Patent of the United States—

1. In a steam-engine, the combination, with 125 a slide-valve provided with a recessed back, of a balance-plate, beneath and against which the valve has a sliding steam-tight connection, and a hollow vertical rod supporting the balance-plate and forming a conduit extending from the chamber at the back of the valve 130 outward into the atmosphere, substantially as set forth.

2. In a steam-engine, the combination of a 135 balance-plate resting upon and forming a

sliding steam-tight connection with the back of the valve, a central rod supporting the balance-plate and extending through a close-fitting orifice in the steam-chest cover for guiding said rod vertically and resisting the side strains caused by the friction of the valve and plate, and means, substantially as described, for balancing the plate from the outside of the steam-chest cover, substantially as set forth.

10 3. In a steam-engine, the combination of an auxiliary cylinder formed upon the outside of the steam-chest cover, a piston fitted therein, a piston-rod extending thence through a close-fitting orifice of the cover into the steam-chest and supporting a balance-plate upon the back of the valve by a ball-joint connection, said steam-chest cover being also perforated for the admission of steam into the cylinder from the chest, substantially as specified.

20 4. In a steam-engine, the combination of a slide-valve with a recessed back, an auxiliary cylinder upon the steam-chest cover, the latter perforated for the admission of steam from the chest into the said cylinder, a piston in said cylinder carrying a hollow piston-rod extending entirely through said cylinder from the outside and passing through a close-fitting orifice in the steam-chest cover, and a balance-plate supported on said piston-rod by a ball-joint connection, arranged and operating substantially as and for the purpose set forth.

25 5. In a steam-engine employing a slide-valve and actuating mechanism, a balance steam-cylinder upon the steam-chest cover and embodied therewith, containing a piston, and central depending piston-rod passing through a bossed

orifice in the steam-chest cover, the latter being perforated to allow free passage of steam into the balance-cylinder, the object of the boss being to furnish rigid support against the lateral strains of friction, substantially as described.

6. In balanced-valve mechanism of the kind described, the combination of an auxiliary cylinder formed upon the steam-chest cover, 45 communicating with the steam-chest interior, as described, the piston therein constructed as described, the hollow piston-rod and its jointure to the balance-plate by ball-bearing, as described, the bossed orifice in the steam- 50 chest cover, and the rigid arch at the top of the auxiliary cylinder, with contained coiled spring surrounding the piston-rod, arranged and operating as described.

7. In a steam-engine, the combination of a 55 slide-valve, a balance-plate resting on the upper face of the same, an auxiliary cylinder upon the steam-chest cover, a piston fitted therein, a piston-rod supporting the balance-plate and secured to said piston, said rod extending outwardly above said cylinder, and a spring secured to and acting upon said rod to assist in preserving contact between the balance-plate and valve, substantially as set forth.

In testimony whereof I have hereunto set 65 my hand in the presence of two subscribing witnesses.

WILLIAM W. LEWIS.
